UNITED STATES PATENT OFFICE.

JOHN TOTTERDALE, OF WARREN, OHIO.

SHEET-METAL CONTAINER.

1,217,667.

Specification of Letters Patent.

Patented Feb. 27, 1917.

Application filed June 10, 1916. Serial No. 102,808.

To all whom it may concern:

Be it known that I, JOHN TOTTERDALE, a citizen of the United States, residing at Warren, in the county of Trumbull and State of Ohio, have invented certain new and useful Improvements in Sheet-Metal Containers, of which the following is a specification.

This invention pertains to a sheet metal container or vessel for storing and shipping 10 nails and other articles, and the invention resides particularly in the novel construction whereby the heads or ends of the container are interlocked with the body there- 15 of, all substantially as shown and described and particularly pointed out in the claim.

In the accompanying drawings, Figure 1 is a perspective view of the container, partially sectioned in the lower portion and 20 partially completed in the lower portion as will hereinafter more fully appear. Fig. 2 is a vertical sectional elevation of the container with the lower head fully engaged and the upper head in position to be 25 engaged.

Fig. 3 is a sectional view of one of the heads or ends of the container, and Fig. 4 is an enlarged sectional detail as hereinafter 30 fully described. Fig. 5 is a blank sheet from which the body of the container is formed.

At least two important original features are believed to be present in the foregoing construction, viz:—the five-fold hand engageable chines and the slotted or slotted 35 interturned flanges or engaging edges of the ends of the body over the flanges of the heads or ends of the container or vessel, as will now appear.

Thus, the body *b* of the vessel, container, 40 cask or package, as one may prefer to term the article, is fashioned from a piece or plate of suitable sheet metal, and which in some instances, at least, is galvanized and has the original shape seen in Fig. 5 after 45 being died or stamped up for the purpose. The said blank is then bent into a tube and the edges 2 thereof interlocked in a seam or fold 3. The end portions or edges of the 50 blank are provided each with several slits or slots 4, of which there may be three or more as shall best promote the subsequent construction and use, and said slots come into the interturned flange 5 of the chine proper 55 and which overlaps the opposite flange 6 of the head or end *h* of the vessel.

A preliminary feature of construction

however, is the formation of the annular beads 7 in body *b* near its ends and which form inside shoulders serving as abutments for the heads and against which the heads 60 are firmly locked by the interturned flanges 5. The said slits, obviously, are important in this arrangement of parts as they allow the said flange 5 to be bent in sections or portions at a time, as seen at the top in Fig. 1, 65 where one section is down and the others are up or unturned. Obviously, also, by this construction of said flange the said sections can be opened or turned back by means of a suitable instrument and the head removed, 70 and both heads or ends are alike in these particulars.

Now, in order to obtain the flanges 5 as and for the purpose set forth, the ends of the body are formed with a three fold thickness, the stock being folded back upon itself with one fold upon the other and the outer fold having the flange 5 as its own outer extension, as seen in Fig. 1. The said 75 folds or laps 8 and 9 are equal in depth to the depth of the chine, and which in a vessel or cask containing nails or in fact any other heavy contents, is a necessary feature of construction so that the vessel can be 80 individually handled by grasping the ends 85 like wooden vessels or kegs heretofore. The said folds 8 and 9 are upon the outside of the vessel and are equal in depth, and the flange 6 on head *h* makes practically a 90 fourth lap or ply and the interturned overlapping edge or flange 5 constitutes a fifth lap or ply, but these latter are on the inside of the chine while the two others, 8 and 9, are on the outside thereof. This brings the 95 stock of the body indicated by 10 below or outside of bead 7 between the two outer folds and the two inner folds or laps, and thus a chine is produced which is five deep in lapped and solid formation and which gives 100 the end and head of the vessel exceptional firmness and provides a practically rigid grip of the requisite depth for the hands. Yet, by means of the slots or slits 4 the flange 5 can be opened and the head removed. 105

Only three splits or slits are shown in the present construction of the extension 5, but as many more may be used as the grade or weight of the metal may seem to require and which will best promote the bending 110 of the sections of the extension lying between said slits.

The outer laps 8 and 9 are of the essence of the present invention because by means thereof I obtain a reinforced chine not possible otherwise and which makes it possible 5 to employ a lighter sheet metal in the manufacture of the cask than would be practicable if such reinforcement were omitted, yet by reason of the construction shown the outer fold 9 is flush or even with the outer 10 surface of the body of the vessel.

What I claim is:

A packing vessel made of sheet metal and having chines five layers of the metal in

depth, two of said layers being on the outside and two inside and comprising a flange 15 on the head of the vessel and an extension from the outer of said outside layers bent inward over said flange and having transverse slits at regular intervals.

In testimony whereof I affix my signature 20 in presence of two witnesses.

JOHN TOTTERDALE.
